United States Patent

Des. 236,831
Patented Sept. 16, 1975

236,831

LAVATORY

George M. Myers, 3148 N. 47th Drive,
Phoenix, Ariz. 85013

Filed June 19, 1974, Ser. No. 480,954

Term of patent 14 years

Int. Cl. D23—02

U.S. Cl. D23—58

FIG. 1 is a perspective view of a lavatory showing my new design;

FIG. 2 is a front elevational view thereof;

FIG. 3 is a rear view thereof; and

FIG. 4 is an end view thereof.

I claim:

The ornamental design for a lavatory, as shown.
